UNITED STATES PATENT OFFICE

DAVID STANLEY CORWIN, OF GREENPORT, NEW YORK

BUILDING CONSTRUCTION

Application filed March 1, 1930. Serial No. 432,535.

This invention relates to building constructions and has particular relation to those building constructions wherein the material may be prepared in a shop or factory and readily assembled at the point where the building is to be erected.

In the building industry there has come to be a need for fabricated constructions which are constructed prior to the time of erection and which may be erected by unskilled labor.

This need has been brought about by the increased cost of labor, the desire or need of an owner to erect his own home, by the necessity of erecting houses in places where skilled labor is not available and in places where the time element has to be considered.

The primary object of this invention is the provision of an improved building construction which will permit of a building to be erected quickly by unskilled labor.

Another object of the invention is the provision of an improved building construction wherein a frame member and a strip on a previously constructed wall member have co-acting means to secure the wall member in place.

A further object of the invention is the provision of a frame and wall construction for a building wherein a frame member is provided with openings and a wall member is provided with projections to cooperate with the openings to hold the members together.

Another and further object of the invention is the provision of a frame and wall construction for a building wherein a wall is provided with a strip secured to the wall member and a frame member with means to coact with the strip to hold the wall member and frame together, the strip being secured in place throughout its length.

Other and further objects will be apparent to those skilled in the art from a reading of the complete specification and claims.

Referring to the drawings wherein I have illustrated an embodiment of my invention;

Figure 1 is a perspective of the invention as applied to an upright wall of a house and showing the studding.

Figure 2 illustrates the method of applying the strips to the wall member.

Figures 3 and 4 are enlarged fragmental perspective views of the strip before and after it is secured to the wall member. 55

Figure 5 is an illustration of the use of my invention both in upright walls and in the walls of roofing.

Figure 6 is a modified form of the invention. 60

Figure 7 is a detail view of parts illustrated on Figure 5.

Figure 8 is a view similar to Figure 5, but of a modified form.

Similar reference characters refer to the same or similar parts throughout the figures of the drawings. 65

In using my invention, I may use any suitable wall construction wherein the wall sections or "boards" are prepared in a factory 70 or mill. One very suitable material which I have found to be advantageous is a woody fibrous material about five eights of an inch or more in thickness, which has a rather open texture and has great heat insulation 75 value. This material is placed upon the market under various names.

My invention not only makes a warm, strong construction when erected, but the wall sections are so prepared in the shop or 80 factory that they are stronger because of the preparation and are more easily handled without injury. My first step in the preparation of the wall, as far as the inside surface next to the frame is concerned, is to coat the 85 same with a suitable flexible water proof covering. Such a suitable covering I have found to be emulsified asphalt. This emulsified asphalt is applied by any suitable method, as by a trowel or by dipping. To this surface which is water-proof and which does not get hard or brittle are applied strips which serve in several capacities. In the first place they furnish a means for securing the board to the frame which is quickly applied 90 to the wall member and which at the same time locates a plurality of securing means in their proper relative location.

In addition, the strips form a reinforcing 100 means for the wall members and also when

along the edges, the strips tend to prevent accidental injury at these edges, due to careless handling.

5 The board I have designated by the reference numeral 10. The coating of emulsified asphalt I have designated 11. The form of strip illustrated in Figures 2, 3 and 4 and at the left on Figure 1, I have designated by the numeral 12.

10 This strip preferably of metal has coacting means, as the tongues 13 extending therefrom and in position to cooperate with complementary means to be described. In order to secure the strip 12 in place on the wall member 11, I have provided suitable securing means. These securing means may be of any suitable character as screws or nails to coat with the holes 14 shown in Figure 3 or the prongs or tangs 15 shown in Figures 15 2, 3 and 4. The prongs or tangs 15 are preferably not at the same angle when driven into the wall member and are preferably placed to extend some slightly toward one end and some toward the opposite end as shown in Figure 2. When the strip is forced down and the prongs enter the wall member there will be a clinching action by the prongs. This will be assisted if the ends of the prongs are slightly bent as shown in Figure 20 3. The prongs at one end may be made straight to assist in getting the strip properly started when being attached. One of the characteristics of a material as emulsified asphalt is that it does not dry and harden immediately. In this way, when the strip is forced downwardly and against the asphalt, the latter by its adhesive action, holds the strip and furnishes an additional holding means to retain the strip in place.

25 40 The frame member which supports the wall members or boards may be of any suitable construction. The illustrated embodiment shows this member as a channel having a web of a width to provide the desired thickness for the wall. The opposite parallel sides of the frame member which I have designated 16, has means complementary to the means 13 on the strips 12. These means on the sides of the channels 16 are the edges of the openings 17. The openings 17 are spaced similarly to the spacing of the tongues 13 and are positioned relative to the tongues 13 that when assembled, the wall member or board 10 will be in its proper relation to the frame members 16. The complementary coacting members 13 and 17 are preferably so constructed that movement in one direction tends to cause the wall member to come closer to the frame member 16 and movement in the opposite direction causes a separation of the two members. In practice of course unless there is some special reason, the parts are arranged so that gravity will assist to keep the parts together.

55 60 65 In Figure 1 I have shown a strip 12^a which

is retained in place solely by screws or nails.

At the near side of the right hand frame member 16 (Fig. 1) I have shown an additional strip 12^a in place to indicate how two opposite walls would be connected to opposite sides of the same frame member 16.

70 In the preceding description I have described an embodiment of an upright wall in which the frame members are studs. I desire to have it understood that the invention is equally applicable to roof construction or 75 ceiling and floor construction or any other place where applicable.

In Figure 5 is a cross section of a roof and 80 side wall construction. In this construction, the frame member 16^a performs a function of the usual studding with an outside wall member or board 10^a which may have any suitable or desirable finish as an imitation of 85 stone or brick, an inside wall 10^b which may be provided with any suitable finish. Both of these walls are preferably constructed with the waterproof covering as already described for the board 10 having the covering 11.

90 Similarly at the upper portion of Figure 5, the frame member 16^b performs the function of a rafter and has secured thereto the wall members or boards 10^c, 10^d. The wall member 10^e is preferably finished as a roof 95 to simulate shingles or in any other suitable manner.

The wall member 10^d may be finished on 100 its under side in any suitable manner. These members 10^c and 10^d are preferably provided with water proof coatings on their surfaces next to the frame member 16^b.

105 In the actual construction of houses, various designs and details of construction may be used. For example, in Figure 5 is illustrated the construction of parts at the corner of a small house. At the top of the frame members or studs 16^a is placed a channel member 20 which is run longitudinal of the tops of the frame members 16^a. In order to 110 properly support the member 20, a portion of the end of the frame member or stud 16^a, is cut and folded down as shown at 18' in Figure 7. The member 20 is then put in place as shown in Figure 5.

115 To support a ceiling, a frame member 16^c is placed on the top of the longitudinal channel member 20.

120 In the erection of the building, it would be convenient to place one wide strip 10, 10^a or 10^b of the wall flat on the ground or floor, the strips 12 having been previously put in place in a shop. The studs 16 or 16^a would now be placed with their coacting means in operative relation to the complementary 125 means on the strips 12. The whole strip with its studs could then be raised together. After being secured in position, the remainder of the side of the building would be put up in a similar manner. If the inside wall 10^b 130

is raised with the studs 16 or 16^a, the outside wall 10^a would not be applied until later, leaving the studs exposed for the purpose of connecting any necessary securing means 5 which may be located between the inside and outside walls.

The top longitudinal member 20 may now be put in place with one flange inside of the inside flange of the studs.

10 Upon this member 20 may be placed the ceiling wall supporting frame member 16^c and upon these members 16^c, may be placed the frame members 16^b, suitably shaped at their ends to coat with adjacent members.

15 These frame members 16^b are secured in place by any suitable means, not shown. After the lower portions and the ceiling supporting members 16^c are secured in place, the outer wall 10^a is placed in position, if not already

20 there. The roofing member 10^c may then be placed.

In placing the roofing member 10^c, it is convenient to place the upper edge so that the strips with the coating means are along the 25 frame members 16^b. Then by sliding the roof member toward and a little beyond its proper place, the tongues will all register with the proper openings. The roof is then slid downward to cause the tongues to lock in place.

30 The roof lining wall 10^d may now be put in position and then the ceiling member 10^c. If a floor member 10^e is used, this is applied last. On the top of this floor member may be placed a flooring 10^g.

35 In Figure 8 is a cross section of a roof and side wall construction of a slightly different type from that shown in Figure 5. In this construction, the frame member 216^a performs a function of the usual studding with 40 an outside wall member or board 210^a which may have any suitable or desirable finish as an imitation of stone or brick, an inside wall 210^b which may be provided with any suitable finish.

45 Both of these walls are preferably constructed with the water-proof covering as already described for the board 10 having the covering 11.

Similarly at the upper portion of Figure 8, 50 the frame member 216^b performs the function of a rafter and has secured thereto the wall members or boards 210^c, 210^d. The wall member 210^c is preferably finished as roof to simulate shingles or in any other suitable manner.

55 The wall member 210^d may be finished on its under side in any suitable manner. These members 210^c and 210^d are preferably provided with water-proof coatings on their surfaces next to the frame member 16^b.

60 At the top of the frame members or studs 216^a is placed a plate member 220 which as shown, is constructed of wood and is run longitudinal of the tops of the frame members 216^a. In order to properly support the member 220 a portion of the end of the frame

member or stud 216^a, is cut and folded down as shown at 216'. The member 220 is then put in place as shown in Figure 8. Two superimposed boards 221, 222 and a finishing strip 223 furnish a cornice. 70

To support a ceiling, a frame member 216^c is placed on the top of the longitudinal cornice member 222.

A convenient method of erecting this wall 75 is as follows:—

After the foundation and first floor are in place, the shoe 224 is laid on its edge adjacent to the place it is to occupy when the wall is erected.

The studs 216^a are now put in place in a horizontal position on the floor with the opening at the bottom of the stud 216^a, provided by the folded portion 216', in proper relation to the shoe 224. The studs are now secured to the shoe 224 and spaced so that the 80 coacting strips of the wall member 210^a will register with the openings in the studs 216^a.

The top plate 220 is now put in place in the openings at the top of the studs. The shoe and top plate are secured in position in 90 any suitable manner as by screws or bolts or nails through holes or slots in the metal studs.

The cornice members 221, 222, 223 are now nailed screwed or bolted to the top plate 220, after which the wall member 210^a is put in 95 place and the whole assembly raised.

After the side is erected, the shoe is secured to the floor and floor beams. When all four sides are erected, the partitions are erected in a similar manner. The ceiling frame members 216^c are now put in place and secured to the cornice members 222, 221 in any suitable manner. The rafter frame members 216^b are now put in place and secured to the 100 ceiling frame members 216^c by bolts or screw 105 or nails through openings in the rafter frame members.

The roof and inner lining wall members 210^c, 210^d may now be put in place after which the inner wall member 210^b and the moulding 110 member 225 may be installed.

It is understood that the proper finishing strips on the roof at corners and between sections would be applied.

In Figure 6, I have shown a modified strip 115 and frame member. In this form, the strip 112 has prongs 115 struck up and into position to be secured to the wall board 110. Nail or screw holes 114 are provided. An opening 113 of the frame member 116 is provided, 120 to the upper edge of which the tongue 117 secures itself when the parts are assembled. It will be noted that the strip 112 is of such a shape that a space is provided at the rear of the opening 113. Furthermore, this 125 illustrated shape gives the strip 112 additional stiffness.

While I have shown and described embodiments and adaptations of my invention, it is to be understood, that these are merely illus- 130

trative and modifications and changes in shape construction and material may be made without departing from the spirit of the invention and within the scope of the appended claims.

Having described my invention, what I claim and desire to secure by Letters Patent is:—

1. A building construction comprising a frame member having spaced openings on opposite sides thereof, a strip of metal having a plurality of projections extending therefrom in the same general direction and at a distance apart equal to the distance apart of the openings in the frame member, the strip having means for attachment to a wall board said projections and openings interlocking when in operative position.
2. A building construction comprising a frame member having a series of openings spaced along its side, a strip of metal having a plurality of projections extending therefrom in the same general direction and at a distance apart equal to the distance apart of the openings in the frame member said projections and openings interlocking when in operative position.
3. A building construction comprising a frame member having a series of openings spaced along its side, a strip of metal having a plurality of projections extending therefrom in the same general direction, on one face and at a distance apart equal to the distance apart of the openings in the frame member and projections extending from the other face, for attachment to a wall board said projections and openings interlocking when in operative position.
4. A building construction comprising a frame member having a series of openings spaced along its side, a strip of metal having a plurality of projections extending therefrom, on one face, and at a distance apart equal to the distance apart of the openings in the frame member and projections extending from the other face at other than a right angle and in the same general direction, for attachment to a wall board.
5. A building construction comprising a frame member and a strip for attachment to a wall board, a series of openings in one and a series of projections on the other, and extending in substantially the same direction, the openings and projections being spaced correspondingly on their respective members.
6. A building construction comprising a frame member and a strip having means for attachment to a wall board, a series of separate, but complementary means on the strip and frame member for attachably securing the two together.
7. A building construction comprising a frame member and a strip for attachment to a wall board, a series of separate, but complementary means on the strip and frame

member for detachably securing the two together in substantially parallel relation, the strip having projecting means for attachment to a wall board.

8. A building construction comprising a frame member in the shape of a channel iron and a strip having means for attachment to a wall board, a series of separate, but complementary means on the strip and channel iron frame member for detachably securing the two together.

9. A building construction comprising a frame member in the shape of a channel iron and a strip having means for attachment to a wall board, a series of openings in one and a series of projections on the other, the openings and projections being spaced correspondingly on their respective members.

10. A building construction comprising a frame member in the shape of a channel iron, the channel iron frame member having a series of openings along two of its sides, and a metal strip for attachment to a wall board and having a plurality of projections extending therefrom on one face and at a distance apart equal to the distance apart of the openings in the frame member and projections extending from the other face at other than a right angle, for attachment to a wall board.

11. A building construction comprising a frame member in the shape of a channel iron, the channel iron frame member having a series of openings along its opposite sides and a metal strip for attachment to a wall board and having a plurality of projections extending therefrom on one face and at a distance apart equal to the distance apart of the corresponding openings in the frame member and projections extending from the other face, for attachment to a wall board.

12. A building construction comprising a frame member in the shape of a channel iron, the channel iron frame member having a series of openings along its side, a strip of metal having a plurality of projections extending therefrom and at a distance apart equal to the distance apart of the openings in the frame member and to secure the channel member and strip in substantially parallel relation.

13. A building construction comprising a frame member in the shape of a channel iron, the channel iron frame member having a series of openings on opposite sides thereof, a strip of metal having a plurality of projections along its length and extending therefrom and at a distance apart equal to the distance apart of the openings in the channel iron frame member, the strip having means for attachment to a wall board.

14. A building construction comprising a frame member and a strip for attachment to a wall board, a series of separate, but complementary means on the strip and frame mem-

ber for detachably securing the two together in substantially parallel relation, the complementary means being so constructed that movement, relatively, in one direction will tend to bring the strip and frame member into closer relationship to each other.

15. A building construction comprising a frame member, a wall member, a viscous material on the frame side of the wall member, a strip secured on the frame side of the frame member and complementary means on the strip and frame member for detachably securing the two together.

16. A building construction comprising a frame member having a plurality of projections extending therefrom and in the same general direction, a strip of metal having a series of openings spaced along its side and at a distance apart equal to the distance apart of the projections, said projections and openings interlocking when in operative position.

17. A building construction comprising a frame member having a plurality of projections extending therefrom and in the same general direction, a flanged strip of metal having a series of openings spaced along its side and at a distance apart equal to the distance apart of the projections, said projections and openings interlocking when in operative position.

In testimony whereof, I hereunto affix my signature.

DAVID STANLEY CORWIN.
